UNITED STATES PATENT OFFICE.

EDMUND F. DOTY, OF NORTH TONAWANDA, NEW YORK.

CENTRIFUGAL PUMP.

Application filed January 5, 1924. Serial No. 684,652.

To all whom it may concern:

Be it known that I, EDMUND F. DOTY, a citizen of the United States, residing at North Tonawanda, in the county of Niagara and State of New York, have invented new and useful Improvements in Centrifugal Pumps, of which the following is a specification.

This invention relates to improvements in centrifugal pumps.

Its chief object is the provision of an efficient pump of this character in which the friction or resistance offered to the flow of water circulating through it is reduced to a minimum.

Another object of the invention is to provide a re-action centrifugal pump which is so constructed that the fluid, after being acted upon by centrifugal force, is diverted approximately at right angles to the plane of rotation of the impeller into the pressure chamber, thereby more efficiently converting the absolute velocity due to tangential and angular velocity into pressure.

A further object is to provide a simple, strong and reliable pump of this character in which the pressure chamber is disposed at one or both sides of the impeller, whereby the direction of flow through said chamber is parallel or substantially parallel with the direction of rotation of the impeller.

In the accompanying drawings:

Figure 1 is a central longitudinal section of a centrifugal pump constructed in accordance with my invention. Figure 2 is a transverse section thereof in line 2—2, Fig. 1.

Similar characters of reference indicate corresponding parts in both figures.

By way of example, the invention is shown in connection with a centrifugal pump of the single stage, double-suction horizontal shaft type, but it is to be understood that the same is equally applicable to single stage pumps of the single suction type or to multi-stage pumps of either the single or double-suction type, or to vertical shaft pumps including any of the aforesaid types.

The numeral 10 indicates the pump-casing having a centrally arranged impeller chamber 11, suction chambers 12 located on opposite sides of the latter in communication therewith and each having a suction inlet 13, and pressure chambers 14 disposed

on opposite sides of the impeller chamber and encircling said suction chambers, the pressure chambers having a common outlet or discharge nozzle 15. Extending centrally through the impeller chamber and suction chambers and through openings 16 on opposite sides of the pump-casing is a horizontal driving shaft 17 journaled in suitable bearings 18 formed on the extensions 19 of said casing.

Arranged within the impeller chamber 11 and secured to the driving shaft is the impeller which preferably comprises a hub 20, a pair of spaced disks or shroud-plates 21, and curved vanes or blades 22 disposed between the latter and spaced apart to provide curved fluid passages 23 opening outwardly or radially and enlarging toward the periphery of the impeller. The shroud-plates are provided with outwardly-facing annular bearing flanges or rims 24 which engage corresponding bearing seats or recesses 25 formed in the pump-casing. As shown in the drawings, the impeller blades extend a suitable distance beyond the peripheral edges of the shroud-plates 21 to provide lateral discharge openings or ports 26 at opposite sides of the impeller which communicate directly with the adjoining pressure chambers 14, the external diameters of the latter being substantially the same as that of the impeller chamber.

Surrounding the impeller and disposed in proximity to the outer edges of the impeller-blades 22 is an impact face or ring 27 which may be cast integral with the pump-casing, as shown in the drawings, or which may be a separate part thereof. The width of this impact ring is preferably equal to or somewhat greater than the corresponding dimensions of the impeller blades. The purpose of this impact ring is to direct or divert the water issuing from the impeller in a lateral direction, or approximately at right angles to the plane of rotation of the impeller through the ports 26 into the adjoining pressure chambers 14. This reactionary effect on the water in this manner results in more efficiently converting the absolute velocity, which is the resultant of both the tangential and angular velocity, into pressure.

It will be noted that the impact ring 27 immediately surrounds the impeller so that there is no appreciable space between the pe-

periphery of the impeller and said impact ring, whereby the water thrown out by the impeller directly impinges against the impact ring and is expelled laterally into the pressure chambers 14.

The shaft-openings 16 of the pump-casing may be fitted with packing glands 28 to prevent leakage.

By arranging the pressure chambers 10 along side the impeller chamber, the course of the fluid from the impeller to the discharge nozzle 15 is in a direction substantially parallel with the plane of rotation of the impeller, thereby reducing the disk 15 friction to a minimum. Furthermore, by this construction, the customary concentric or volute chamber surrounding the impeller and the usual clearance spaces are dispensed with, thereby eliminating the shock and 20 friction losses incident to this type of pump.

I claim as my invention:

1. A centrifugal pump, comprising a casing having an inlet and a discharge, an impeller chamber in communication with said inlet, an impeller including blades, open at its periphery and rotatably mounted in said chamber, and a pressure chamber arranged at one side of said impeller chamber and communicating with the same and with said discharge, the peripheral edges of the blades being parallel with and extending to the inner wall of the impeller chamber, said impeller having lateral discharge openings intersecting with the periphery thereof and communicating with said pressure chamber and said inner wall of the impeller chamber constituting an impact face for directing the fluid through said discharge openings at substantially right angles to the plane of rotation of the impeller.

2. A centrifugal pump, comprising a casing having an inlet and a discharge, an impeller chamber in communication with said inlet, an impeller rotatably mounted in said chamber, a pressure chamber arranged at one side of said impeller chamber and communicating with said discharge, and a chamberless member on said casing and immediately surrounding said impeller for diverting the fluid issuing therefrom at right

angles to the plane of its rotation into said pressure chamber.

3. A centrifugal pump, comprising a casing having an inlet and a discharge, an impeller chamber in communication with said inlet, an impeller having lateral discharge openings rotatably mounted in said chamber, a pressure chamber arranged at one side of said impeller chamber and communicating with the same and with said discharge, and reactionary means surrounding the impeller chamber and in proximity to the periphery of the impeller for diverting the fluid through the discharge openings of the latter into said pressure chamber, the impact face of said reactionary means being substantially parallel with the axis of said impeller.

4. A centrifugal pump, comprising a casing having an inlet and a discharge, an impeller chamber in communication with said inlet, an impeller open at its periphery rotatably mounted in said chamber, a pressure chamber arranged at one side of said impeller chamber and communicating with said discharge, the impeller having lateral discharge openings near its periphery for establishing communication between said impeller and said pressure chamber, and a stationery impact member disconnected from and surrounding said impeller in proximity to its periphery, said impact member being straight transversely of its face.

5. A centrifugal pump, comprising a casing having an inlet and a discharge, an impeller chamber arranged substantially centrally of said casing and communicating with said inlet, an impeller open at its periphery mounted in said chamber, pressure chambers located on opposite sides of the impeller chamber and communicating with said discharge, the impeller having lateral openings in its opposite sides adjoining the periphery thereof for establishing communication between the impeller and said pressure chambers, and an impact ring carried by said casing and lying in proximity to and in the plane of said impeller.

EDMUND F. DOTY.
